PACKING OR WRAPPER, ESPECIALLY USEFUL FOR SHAMPOOING AND HAIR DYEING MATERIALS

Erich Sievers, Berlin, Germany

Application July 16, 1931, Serial No. 551,286, and
in Czechoslovakia, Sweden, Austria, and
Norway May 4, 1931

1 Claim. (Cl. 2—174)

This invention relates to a packing or wrapper especially useful for shampooing and hair dyeing materials which packing or wrapper in well-known manner consists of a bag containing the 5 shampooing or other material and a preserving cover consisting of a vitreous film, such as cellophane or such like.

The feature of the invention resides in the fact that the preserving cover which, hitherto, was 10 useless and for this reason thrown away, can be utilized. This, according to the present invention, is thereby attained in that with the preserving cover is combined a number of elastics or rubber cords or one such elastic or rubber cord only and 15 that further said cover is so formed that after ripping it open it may be united with the elastic or rubber cord and then utilized as a preserving mask for the face of the user during the shampooing and washing action.

20 In the accompanying drawing is shown an example of the subject matter of the invention; Fig. 1 is a perspective view of the packing viewed from one side, and Fig. 2 is a similar representation viewed from the other side. Fig. 1a is a 25 transversal section of the new packing, while Fig. 2a shows, on a larger scale, a transversal section of the edge of the packing. Figs. 3, 3a and b are representations illustrating the utilization of the 30 cover as a preserving mask.

30 A is a bag containing the shampooing material and B is a wrapper which, for example, contains a hair-glossing powder serving for treating the hair. These containers A and B are enclosed by the protective or preserving cover a which suitably consists of a vitreous film of cellophane or 35 such like. Elastics or rubber-cords b embrace the wrapper B and are also surrounded by the preserving or protective cover a.

As shown in Figs. 2 and 3 the preserving cover

a at its two edges adjoining each other is strengthened by a lining c of card-board or such like. Said lining at both ends and in the center is provided with pairs of slots d so that, after 60 ripping up the lining along a line of perforations provided in the central part of said lining, and after introducing the elastics or rubber cords b into the slots d of the strengthening linings, the preserving cover a, as shown in Fig. 3a, by pulling the elastics over the ears of the user, may be 65 used as facial preservative. The edge of the cellophane sheet may then be strained in such a manner that it is closely applied to the forehead of the user and that no liquid is allowed to wet 70 parts of his face.

It is still more suitable to fold the cover illustrated in Fig. 3 in the center along the dotted lines shown in Figs. 2 and 3 and to attach the elastics by means of the slots d situated one upon the other, as shown in Fig. 3b. Hereby not only 75 a more suitable and smoother application of the preserving mask near the temples but also a secure fastening of the mask is warranted because the laterally strengthened edges c are strained as well in their lower as their upper 80 parts, so that these edges are closely applied on their whole length to the face and no liquid is allowed to enter here.

What I claim is:

A device of the character described comprising 85 a sheet of transparent film material, strips of reinforcing material fixed to opposed marginal edges of said sheet, said strips having slots formed at the end portions and opening at the extremities 90 of the strips for engagement with rubber bands whereby said sheet may be stretched across the face by passing the rubber bands about the ears.
